UNITED STATES PATENT OFFICE.

HENRY NORDMANN, OF BROOKLYN, NEW YORK.

DESIGN FOR A CARPET.

SPECIFICATION forming part of Design No. 11,833, dated June 29, 1880.

Application filed February 12, 1880. Term of patent 3½ years.

To all whom it may concern:

Be it known that I, HENRY NORDMANN, of the city, county, and State of New York, have invented a new and original Design for Carpets, of which the following is a specification.

This invention relates to a new and original design for carpets, oil-cloths, and similar fabrics. It consists in the novel grouping and configuration of figures hereinafter more fully described.

The accompanying photograph illustrates a face view of a carpet having my new design.

The background is composed of square figures *a*, formed of parallel lines, and diamond figures *b*, placed in alternate squares *a*. On one side is a group, *A*, composed of two geometrical figures, *d d*, placed at right angles to each other, and of a rectangular figure, *e*, and a geometrical figure, *f*, placed obliquely between the two figures *d d*. Flowers *g* are superposed on the figures of group *A*, so as to partially cover the same.

Opposite the group *A* is a group, *B*, composed of a geometrical figure, *h*, a zigzag-shaped lower border, *h'*, and of a bunch of flowers, *i*, which connects and partially covers the figures *h h'*.

In the center of the field is a group, *C*, composed of rectangular figures *j j'*, placed parallel to each other, a rectangular figure, *l*, placed obliquely against one end of figure *j'*, and angular scrolls *m m'*, that extend from the opposite end of figure *j'*.

Close to the group *B* is a vase-shaped ornament, *D*, having vines *n o p* branching from it. The vine *n* connects the vase *D* and group *B*, and vine *p* connects the vase with the group *A*, and, traversing said group, extends to group *C*. A branch, *q*, extends from the central group, *C*, upward.

Above the group *C* is a group, *D'*, composed of geometrical figures *v v'* and flowers branching from figure *v'*, of peculiar form, which figures are ornamented with flowers, as shown.

Between the groups *C* and *D'*, and a little to one side, is a group, *E*, formed of an obliquely placed rectangular figure, *s*, and overlaid flowers and leaves, and on the opposite side is a group, *F*, composed of three fan-shaped figures, *t u v*, the central figure, *u*, overlapping and connecting the figures *t v*. The group *F* overlies a flowered vine, *w*.

I claim—

1. The design for a carpet, consisting of group *A*, which is composed of the figures *d*, *e*, and *f*, substantially as shown.

2. The design for a carpet, consisting of group *B*, composed of the figures *h* and *h'*, substantially as shown.

3. The design for a carpet, consisting of group *C*, composed of the figures *j j'*, *l*, *m*, and *m'*, substantially as shown.

4. The design for a carpet, consisting of group *E*, composed of the figure *s* and overlaid flowers and leaves, substantially as shown.

5. The design for a carpet, consisting of group *D'*, composed of the figures *v* and *v'*, substantially as shown.

6. The design for a carpet, consisting of group *F*, composed of the figures *t*, *u*, and *v*, substantially as shown.

7. The design for a carpet, consisting of the vase-shaped ornament *D* and vines *n o p*, extending from it, substantially as shown.

8. The design for a carpet, consisting of the group *A* and vase *D* and vine *p*, substantially as shown.

9. The design for a carpet, consisting of the group *B*, vase *D*, and vine *n*, substantially as shown.

10. The design for a carpet, consisting of the groups *A* and *C* and vine *p*, substantially as shown.

11. The design for a carpet, consisting of the groups *A B C*, vase *D*, and vines *n o p*, substantially as shown.

12. The design for a carpet, consisting of the group *C* and branch or spray *q*, substantially as shown.

13. The design for a carpet, consisting of background *a b* and figures *A*, *B*, *C*, *D*, *D'*, *E*, and *F'*, and of the floral ornaments, substantially as shown.

HENRY NORDMANN.
